UNITED STATES PATENT OFFICE.

CYRUS W. BASSETT, OF MAPLEWOOD, NEW JERSEY, ASSIGNOR TO ELEVATOR SUPPLIES COMPANY, INC., OF HOBOKEN, NEW JERSEY, A CORPORATION OF NEW JERSEY.

SAFETY DEVICE FOR ELEVATOR OPERATION.

Application filed May 8, 1925. Serial No. 28,814.

The present invention relates to safety devices for elevator operation, and more particularly to improvements in locking and control means for preventing operation or 5 for permitting operation of an elevator car except under certain limiting conditions.

In the operation of passenger elevators it is of great importance that means be provided whereby it will be impossible to operate the elevators while at a floor landing with the shaft doors in open position. The means must be of a form which cannot be readily disconnected or rendered inoperative by unauthorized persons, and the various 15 parts of the mechanism must be so interconnected that when the elevator is in operation the various safety devices must of necessity operate. The invention, which will herein-after be described, provides certain novel and 20 improved features over the means heretofore employed, which serve to greatly increase the safety of operation, and results in an increased efficiency in elevator operation.

The primary object of the invention is to 25 provide new and improved means in safety devices for elevator operation.

Another object of the invention is to provide a combination of correlated devices which operate interdependently, one device 30 serving as a check and locking means for other parts, so that the elevator cannot operate unless the various parts are in the required correlated positions to permit safe operation of the elevator.

35 A further object of the invention is to simplify and improve safety devices in connection with elevator operation so as to render the actuation of the parts interdependent and positive in operation.

With these and other objects in view the invention comprises the various features hereinafter described and particularly defined in the claims.

The various features of my invention are 45 illustrated in the accompanying drawings showing the preferred embodiment of my invention, in which:—

Figure 1 is a vertical sectional view of a

portion of an elevator hatchway, and an elevator car therein, the car being shown at a 50 landing with the shaft doors in closed position and the car gate in open position, and the various safety devices embodying my invention being shown in relation thereto;

Figure 2 is a detail view in elevation showing certain features of the invention and illustrating the relative positions of the toggle levers and various parts connected therewith when the elevator doors are in closed position;

Figure 3 is an enlarged detail view in elevation showing the relative positions of the toggle levers and parts connected therewith when the elevator doors are in open position;

Figure 4 is a part sectional view in elevation taken on the line 4—4 of Figure 5, showing a section of a car at a landing and the car controller therein, which is shown in neutral position, in combination with 70 means for locking the controller and showing also means for operating the latch release rod;

Figure 5 is a sectional plan view of a portion of the elevator car and shaft, showing 75 the relative positions of the controller and parts associated therewith, when the elevator doors are in closed position;

Figure 6 is an end view of the controller taken from the left in Figure 4;

Figure 7 is a detailed view showing the preferred form of car cam for actuating a lever operatively connected to the latch release rod;

Figure 8 is a detailed view showing the 85 preferred form of levers for transmitting motion from the car cam to the latch release rod and showing also door locking means operatively connected to the release rod;

Figure 9 is a plan view showing a portion 90 of the elevator hatchway in section showing the means for locking the door in open position and the tripping means attached to the release rod for releasing the locking means; and

Figure 10 is a detailed plan view of the

latch and latch lock taken on the section line 10—10 of Figure 3.

Referring more particularly to the drawings, the numerals 10, 12 indicate elevator shaft doors which are mounted in the usual manner upon overhead guide rails 14, 16, the doors being connected to door closer arms or toggle levers 18 to which a handle 20 of the usual form is connected for hand operation.

10 Operatively connected to the toggle levers 18 are a door closing and check mechanism 22 and a switch 40, the latter being in circuit with the elevator operating circuit and serving to break the circuit when the elevator 15 doors are opened.

In Figure 1 the hatchway doors or elevator shaft doors are shown in the closed position, as seen from the interior of the hatchway, the car gate being indicated in 20 open position. The door closer and check mechanism 22, above referred to, which is connected to the levers 18, may be of any desired form such as the so-called hand check, for example, which operates to oppose the 25 opening movement of the elevator doors when the doors are opened by hand, and to return the doors to closed position when the handle on the toggle levers is released. In place of the hand check I may employ 30 a power check or, in other words, a device of the same kind which is pneumatically operated, various forms of which are in common use.

The door closer and check mechanism 22 35 may be mounted in any suitable manner, although I preferably mount the mechanism by attaching one end thereof to a bracket 23 to which it is pivotally connected, the bracket being attached to the side walls of 40 the hatchway or mounted on a back plate 25, and attaching the other end through the piston rod 24 to a lug 26 or other suitable connecting means on the toggle levers 18. The piston rod 24 is attached to a piston or 45 plunger within the cylinder which operates in a liquid to provide cushioning action. Mounted in the cylinder around the piston rod 24 is a spring which is compressed when the elevator doors are opened, the spring 50 serving to return the elevator doors to closed position. The operation of the apparatus with power operation is substantially the same as with the hand check except that the movement of the doors is controlled by a lever which operates a valve to admit or exhaust pressure fluid to and from the check mechanism.

In order to prevent the opening of the elevator shaft doors except when the elevator car is arrested in the shaft within the predetermined distance of the landing, a latch 28 is provided to cooperate with the toggle levers to normally hold the door closer arms and parts connected thereto in locked 65 position. Operatively connected to the

latch 28 is a release mechanism for disconnecting or unlocking the latch when the car is in a suitable position and it is desired to open the elevator doors. The latch 28 is preferably pivoted on a bracket 30, which 70 may be integral with the bracket member 32, if desired, to which the door closer arms are connected. In order to lock the toggle levers a latch lock 34 is provided which is preferably attached to the inner link 31 75 of the toggle levers at a point in proximity to the bracket 32. The latch lock is preferably of a form so as to project downwardly and laterally from the toggle lever arm and to engage the latch under the hook portion 29 thereof in the locked position of the latch. The latch lock 34 may be made integral with the connecting member or lug through which the piston rod 24 is connected to the toggle levers, although a separate connecting means may be employed if desired, for connecting the piston rod 24 to the toggle levers.

In order that the latch 28 may be raised to unlock the toggle levers when the car 90 is within a suitable distance of the landing an operating mechanism is provided, the parts of which are adapted to cooperate only when the elevator car is suitably positioned with respect to the floor landing. In order to accomplish this result one portion 95 of the mechanism is attached to or installed in the elevator car and the other portion is operatively connected to the latch at the landing, and cam means or other tripping mechanism is provided through which the parts may cooperate to attain the desired action.

The mechanism which is directly associated with the latch member at the landing is preferably mounted on the sill at the landing and comprises a latch release rod 36 which is operatively connected at its upper end with the latch member 28 by means of a lug or other suitable connecting 105 means 41 which is attached to the latch member by means of a swivel joint connection. The release rod passes through an opening in the lug 41 and is free to move relatively to the lug within certain limits. Attached to the release rod below the lug 41 is a lifting member 37 adapted to contact with the lug 41 when the rod is raised, thereby lifting the latch 28 out of locked 110 position. Attached to the release rod 36 above the lug 41 are lock nuts 39 or their equivalent by means of which the downward movement of the release rod is limited.

When the latch member 28 is raised the latch lock 34 is then released from locked 125 position and the toggle levers 18 may then be operated, whereby the link 31 of the toggle will be raised or rotated about its point of connection to the bracket 32, thereby bringing the latch lock 34 upwardly into 130

the position shown in Figure 3. In this position the latch lock engages the nose portion of the latch 28 and holds the latch in raised position, as illustrated in Figure 5 3, until the toggle levers are again operated to bring the link member 31 into its original position, whereby the elevator doors are closed.

In order to operate the switch 40, so as to 10 open the controller circuit when the elevator doors are opened, and in order to make the operation of the switch dependent on the operation of the latch member 28, so as to have the controller circuit closed when the 15 toggle levers are locked, the switch operating lever 44 is connected to the latch 28 by my suitable means such as a connecting rod 42, for example, which is preferably connected thereto by means of a swivel joint 20 connection 46. The operating lever 44 of the switch is connected to a movable member within the switch, the movable member having conducting portions and non-conducting portions adapted, through engagement with conducting bars attached to the 25 circuit terminals, to open and close the controller circuit. In the position of the lever 44 shown in Figure 2, in which the toggle levers are in closed position, the conducting portions of the movable member are in contact with the conducting bars, whereby the 30 circuit through the switch terminals is closed. In the position of the movable member as shown in Figure 3, the circuit is open, 35 the non-conducting portions of the movable member being in contact with the conducting bars.

Any suitable form of connection between the latch 28 and the switch 40 may be employed, by means of which the relative positions of the parts may be adjusted so as to attain operation when the parts of the mechanism have reached certain predetermined positions. It is, in general, desirable 45 that the relative positions of the parts should be so adjusted that the circuit through the switch 44 will close at the moment the elevator doors reach their closed position, and the latch 28 engages the latch lock 34, whereby 50 the toggle levers are locked in position. In order, when the elevator doors have been opened, to retain the doors in their open position, a door lock 48 is provided for engaging a catch or tongue 54 suitably attached 55 to one of the doors whereby the doors are held in their full open position until the lock 48 is released by a suitable releasing mechanism. The door lock 48 may be mounted in any suitable manner, although it is 60 preferably pivotally connected to a bracket member 50 attached to the back plate 25.

In order to disconnect or unfasten the door lock, when the elevator doors are to be released from their full open position, an 65 adjustable trip 52 (see Fig. 9) is provided

which is preferably mounted on the release rod 36 in a suitable position, so that when the release rod is raised the trip will engage and raise the door lock 48 whereby the lock will be disconnected from the catch or tongue 54, attached to one of the elevator doors. During the opening movement of the elevator doors 10, 12, the catch or tongue 54, which is preferably mounted on a bracket 55 (see Fig. 8) on the back of the forward door 12, moves under one of the teeth 49 of the locking bar 48, whereby the doors will be held in their open position until the lock is released by the tripping member 52. The release rod 36 is preferably mounted in a guide member or bracket 56 and a spring member 58 is mounted on the rod below the bracket so as to return the release rod to its original position, after it has been operated to release the latch 28 from its locked position, or to release the door lock 48. The spring 58 is preferably held in position on the rod by means of a collar or washer 60 attached to the rod 36, as is shown in Figures 2 and 8. 90

For the purpose of operating the rod 36 it is connected at its lower end to a suitable operating means or connecting means, which comprises preferably a bell crank lever 62, pivotally mounted on a bracket 64, the bracket being mounted upon the sill 66 at the landing, or in any other suitable position. The bell crank lever 62 is connected through an adjustable connecting rod 72 to a second lever 68, which is preferably pivotally mounted on a bracket 70. Connected to the lever 68 is a roller 74 which is mounted so as to project laterally into the elevator shaft a suitable distance so that it may engage a tripping mechanism mounted on the elevator car without coming into contact with the elevator. The tripping mechanism may be of any suitable form, although I preferably employ a cam member 76, shown in Fig. 2, which may be mounted on a lever 78, pivotally attached to the side of the car by means of a bolt or other fastening means 80 (see Figs. 4 and 7). 105

Mounted preferably on the side of the elevator car, at the side of the rod or lever 78, is a stop member 82 adapted to limit the return movement of the lever. In order to cushion the movement of the lever against the stop a suitable cushioning means 83, such as rubber, for example, is mounted on the stop, which serves also to render the movement of the lever against the stop substantially noiseless. Mounted also on the stop is a guide member 84 preferably in the form of a rod, adapted to pass through the opening 85 of a bracket 86, mounted on the lever 78, which cooperates with the rod 84 to guide the lever 78 in its movements toward and away from the stop member 82, and serves also for holding a spring member 88 110 115 120 125 130

which is mounted on the rod between the bracket 86 and a nut or other holding means 90 at the end of the rod. As the lever 78 moves away from the stop 82, the spring member 88 is compressed, and tends to return the lever to its original position against the stop 82 as soon as the means actuating the lever is released.

Any suitable means adapted for operating the lever 78 to move the cam 76 into and out of tripping position with respect to the roller 74 may be employed. The means which I preferably employ for this purpose comprises a system of levers connected to the cam lever and a foot pedal located within the car and operatively connected to the levers. The system of levers may be mounted in any suitable manner although I preferably employ a shaft 94 mounted in bearings 96 in a bracket 98 under the car to which the cam lever 76 is operatively connected. The shaft 94 is rigidly connected or keyed to an arm 100 having a bearing 102 in its outer end in which is a shaft member 104 which in turn is connected to the lower end of the cam lever 78. At the end of the shaft 94, opposite to that at which the lever 100 is connected, there is mounted a lever 106, which projects a suitable distance under the car so as to give the desired leverage, and connects with a foot pedal 108, by means of which the lever system is directly operated. The foot pedal 108 has a stem 112 which passes through a suitable opening in the floor of the car, which serves to guide it in its movement, the pedal being normally maintained in its raised position by means of the spring 88 which holds the lever 78 in its retracted position. The pedal 108 is preferably attached to the arm 106 through a connecting member or lug 110 pivotally attached to the arm 106 and attached to the lower end of the pedal stem 112 by any suitable connecting means such as a screw thread connection 114.

For the purpose of locking the controller in neutral position when the pedal 108 is operated to release the latch 28, and thereby permit the toggle levers 18 to be operated to open the elevator doors, an arm or lever 116 is attached or keyed at one end to the shaft 94, preferably between bearings 96, and is pivotally connected at its other end to a control locking bar or rod 118, which passes upwardly through the floor of the car, and through a guide member 120, preferably at the rear of the car controller 122, into a position in which it may engage a suitable locking means operatively connected to the controller crank 125. The locking means connected to the car controller crank 125 comprises preferably a member 132 having a slot 138 therein and having two laterally projecting arms 134, 136, the inner side of which is adapted to

contact with the rod 118 or a suitable lug or contacting member 140 thereon so as to prevent the upward movement of the control locking bar 118 except when the crank 125 is in neutral position of the controller. The laterally projecting arms 134 and 136 extend preferably concentrically with respect to the center of rotation of the controller crank 125 and the slot 138 between the side arms 134 and 136 is preferably of a size so as to substantially fit the member 140 so as to prevent substantial movement of the crank arm 125 when the member 140 on the rod 118 has been moved into place in the slot.

The pedal 108 can only be depressed obviously when the controller crank 125 has been moved into neutral position, whereby the slot 138 is brought into registration with the locking member 140 on the rod 118. As soon as the pedal 108 is depressed the member 140 moves into the slot 138, locking the controller, and simultaneously the lever 78 is operated to extend the car cam 76 into the position in which it moves the roller 74 and operates the latch release rod 36, as has been explained above. As soon as the toggle levers are operated to open the elevator doors, the controller switch 40 is opened and the elevator cannot thereafter be operated until the toggle levers are again closed and the controller locking bar has been withdrawn out of engagement with the slot 138. If for any reason the car switch handle is not in neutral position when pressure is exerted on the foot pedal 108, the lug 140 strikes on one of the arms 134 or 136 and prevents the foot pedal from being depressed the requisite distance to bring the car cam 76 into operative position with respect to the roller 74.

The complete operation of the mechanism may be briefly described as follows:

Assume that the operator has stopped the car at a landing so that the car floor is within three inches of the landing floor. The controller handle 126 is then in neutral position, the latch 28 is in locked position and the car cam 76 is in its retracted position. The operator, in order to unlock the latch 28 so as to permit opening of the shaft doors, exerts a downward pressure on the foot pedal 108 whereby the control locking bar 118 moves upwardly, bringing the lug 140 into engagement with the slot 138 to lock the controller in neutral position and the car cam 76 is brought into contact with the roller 74. Through the movement of the roller 74 to the left by means of the cam 76 the upper portion of the lever 68 is moved to the right, whereby the bell crank lever 62 is rotated so as to move the latch release rod 36 upwardly, thereby lifting the latch 28 and releasing the latch lock 34. As soon as the latch 28 has moved out of engagement with the latch lock 34, the door closer

arms or toggle levers 18 are free to be operated to cause opening of the shaft doors. Through the upward movement of the latch 28 the switch 40 is opened by means of the rod 42 attached to the latch 28 and the controller circuit is thereby broken, whereby it will be impossible to operate the elevator until the switch 40 is again returned to its closed circuit position.

- 10 When the elevator doors 10, 12 are opened by means of the toggle levers 18, the handle 20 is moved downwardly and the link arm 31 is moved upwardly, bringing the latch lock 34 into the position indicated in Figure 3, in which the latch 28 is held in raised position by means of the latch lock. As soon as the latch 28 has been raised by means of the latch release rod 36 and the elevator doors have been opened the pressure on the 20 foot pedal 108 may then be released, whereby the car cam 76 is retracted by means of the spring 88, and the release rod 36, through the action of the spring 58, is moved downwardly until the nut 39 thereon engages the 25 lug 41, whereby the roller 74 is returned to its original position, although the latch 28 remains in raised position.

When the elevator doors are brought into full open position the catch or lug 54 at the 30 rear of the forward door 12 engages and lifts the door lock 48 (see Fig. 8), which then engages the catch at one of the teeth 49, whereby the doors are retained in full open position until the member 48 is unlocked, 35 which is accomplished by exerting pressure on the foot pedal 108 which moves the cam 76 into contact with the roller 74, which lifts the release rod 36 whereby the member 52 then engages the latch or door lock 48, 40 moving it out of engagement with the latch 54, thereby releasing the doors.

During the opening movement of the elevator door energy is stored up in the spring in the door closer and check mechanism 22, 45 whereby, when the door lock is released, the doors are returned to their closed position through the force exerted by the spring.

While the elevator doors are in open position and held by the door lock 48 the operator may obviously remove his foot from the 50 pedal, whereby the movable cam 76 is retracted by the action of the spring 88 into engagement with the stop 82. Through this movement the locking bar 118 is retracted 55 and the lug 140 thereon is brought out of engagement with the slot 138 in the member 132, thereby releasing the controller handle from its locked position.

The unlocking of the controller handle 60 does not permit operation of the elevator while the elevator doors are in open position, however, as the controller circuit remains open until the switch 40 is closed, which can be accomplished only through the door clos-

ing movement and locking of the toggle 65 levers.

In order to return the elevator doors to the closed position the handle 20 is released by the operator, or if the doors have been opened to their full open position so as to 70 be locked by means of the door lock 48, the operator exerts a downward pressure on the pedal 108 which raises the release rod 36, whereby the tripping member 52 raises the door lock 48, releasing the catch 54 and permitting the return movement of the doors by the action of the spring in the door closer cylinder. The downward movement of the pedal also locks the controller in neutral position, as above explained. During the final 80 closing movement of the doors the movement is checked by means of the checking device in the door operating cylinder, and as the door closer arms return to their original position, the latch hook 34 moves under the 85 hook 29 of the latch, thereby locking the latch 28 in closed position and simultaneously closing the switch 40 through the movement of the rod 42, attached to the latch, which operates the switch lever 44. As soon 90 as the pressure on the foot pedal is released the car cam 76 is retracted and the controller locking bar 118 is simultaneously withdrawn out of engagement with the controller, thereby permitting operation of the elevator car. 95

If, in the movement of the toggle levers to closed position the latch 28 should remain raised during the first part of the closing movement, the projection 35 on the latch lock 34 will strike against the projection or 100 lug 27 connected to the latch 28, whereby the latch will be forced into closing position. In the final closing movement, as soon as the foot pedal 108 is released the release rod 36 will be forced downwardly by means of the 105 spring 58 whereby the nuts 39 at the top of the rod will come into contact with the lug 41, thereby assisting also in the final closing movement of the latch in which it becomes locked in position over the latch 110 lock 34. In the locked position of the toggle levers any tendency to open the toggle levers will put the latch 28 and the latch lock 34 in tension.

It is to be understood that the device 115 which has been described constitutes only the preferred embodiment of my invention and that various changes or modifications may be made therein without departing from the spirit or scope of the invention as defined 120 in the claims.

What I claim as new is:—

1. A control mechanism for elevator operation comprising in combination an elevator car, a controller in said car, a shaft door, toggle levers for operating said door, a door closing and check mechanism connected to said toggle levers, means for locking said

- toggle levers to prevent operation thereof when the elevator car is in motion comprising a latch, a latch lock on said toggle levers adapted to cooperate with said latch to normally hold said toggle levers in locked position, a release rod operatively mounted in connection with the said latch to release, when actuated, the said latch from the said latch lock, a lever operatively connected to said release rod, a cam mounted on said car for tripping said lever, means for moving said cam into tripping position with respect to said lever, means operatively connected to said cam to lock the controller in neutral position when said cam is in tripping position, and means for preventing movement of the cam into tripping position when the controller is out of neutral position.

2. A control mechanism for elevator operation comprising in combination an elevator car, a shaft door, toggle levers for operating said door, a power operated door closing and check mechanism connected to said toggle levers to control the movements of said door, means for locking the said toggle levers to prevent opening thereof when the elevator car is in motion, a controller in said car, an electric switch in circuit with said controller, means for operatively connecting said switch to said locking means so as to open the controller circuit when said locking means is operated to unlock said toggle levers, means within the elevator car to unlock said locking means, means for simultaneously locking said controller in neutral position, means to prevent the unlocking of the toggle lever locking means when said controller is out of neutral position, means for locking said door in open position, and means accessible within the said car for unlocking said door locking means when and only when said controller is in neutral position.

3. A control mechanism for elevator operation which comprises in combination an elevator car, a controller in said car, a shaft door, toggle levers for operating said door, a door closing and check mechanism connected to said toggle levers, an electric switch in circuit with said controller, a latch, means operatively connecting said switch with said latch so as to open the controller circuit when said latch is operated, a latch lock connected to said toggle levers and normally held in locked position by said latch whereby the circuit through said switch will be closed when said toggle levers are in closed position, a latch release rod connected to said latch, means operable within said elevator car for actuating said release rod to unlock said latch lock when the elevator car is arrested in the shaft within a predetermined distance of the landing at which said shaft door is to be opened, and means for returning the said release rod to its original position without returning said latch to locked position when said actuating means within the elevator car is released.

4. In a device of the kind described, an elevator door, toggle levers connected to said door and pivotally mounted on a stationary surface, a latch pivotally mounted below said toggle levers on said surface, a latch lock connected to a link of the toggle levers and extending under said latch so as to cooperate therewith to lock said toggle levers in the position in which said elevator door is closed, means for actuating the said latch comprising a rod mounted in proximity thereto and adapted to raise the latch when said rod is actuated from within the elevator car, means within the elevator car for raising the said release rod and to lift said latch when the elevator car is within a predetermined distance of the landing at the said door, means on the said latch lock for holding said latch in raised position while the said toggle levers are in open position, and means for positively returning said latch to its locked position when the said latch lock has been returned to its position corresponding to the closed position of the elevator door.

5. In a device of the kind described, the combination of toggle levers, means for locking the said levers in closed position comprising members connected therewith so as to be subjected to tension when it is attempted to open the levers in the locked position of said locking members, means for unlocking the said locking means operable from within the elevator car, and means, positively actuated, for bringing the said members into locking position when said toggle levers are brought into closed position.

6. In a device of the kind described, an elevator door, toggle levers connected to said door, a latch and latch lock operatively mounted with respect to said toggle levers to lock said toggle levers when brought into the position corresponding to the closed position of said elevator door, and means connected to said latch lock to hold said latch in raised position when said toggle levers are in the position corresponding to the open position of said elevator doors.

7. In a device of the kind described, an elevator door, toggle levers connected to said door, a latch pivotally mounted below said toggle levers, a latch lock connected to a link of the toggle levers and extending under said latch so as to cooperate therewith to lock said toggle levers in the position in which said elevator door is closed, means for actuating the said latch comprising a rod mounted in proximity thereto and adapted to raise the latch when said rod is actuated from within the elevator car, means within

the elevator car for raising the said release raised position, and means operatively connected to said release rod for returning said 10 rod and to lift said latch when the elevator nected to said release rod for returning said latch to its locked position when the said car is within a predetermined distance of the landing at the said door, means on the means within the elevator car for raising the said release rod is released.

5 said latch lock for holding said latch in raised position while the said toggle levers are in open position, means connected to day of May 1925.

said latch lock for lowering said latch from

Signed at New York city, N. Y., this 5th
CYRUS W. BASSETT.
